attorney.

UNITED STATES PATENT OFFICE.

DAVID B. KERR, OF PHILADELPHIA, PENNSYLVANIA.

WOVEN FABRIC.

SPECIFICATION forming part of Letters Patent No. 416,225, dated December 3, 1889.

Application filed August 8, 1888. Serial No. 282,291. (Specimens.)

To all whom it may concern:

Be it known that I, DAVID B. KERR, a citizen of the United States, residing at Philadelphia, in the county of Philadelphia and 5 State of Pennsylvania, have invented a new and useful Improvement in Woven Fabrics; and I do hereby declare that the following, taken in connection with the annexed drawings, is a full, clear, and exact description thereof, and is sufficient to enable others skilled as weavers to practice my invention.

The object of my invention is to apply to a greater variety of woven goods the capacity of ornamental shading to woven figured fabrics by the interweaving of warp and weft threads different in color, explained in Patent No. 353,790, granted to me December 7, 1886. In said Letters Patent my invention is there described as "consisting in the combination of two warps of the same color, mounted each on a separate beam, with two or more colored weft-threads. The warp-threads are so arranged in the loom-harness as to work in pairs, with a binder warp-thread in the 25 center of each pair."

My present improvement applies to fabrics known to the trade as "*petit pointe*," with satin face, and other goods composed of two fabrics different in texture which intersect 30 each other to produce ornamental grounds and figures, and also to fabrics with two figuring-warps, each of a different color, for the above purposes. Satin (twilled) fabrics, according to fineness, contain from one hundred 35 to two hundred or more warp-threads per inch, which are operated singly for twilling purposes, and when combined with colored weft-threads form ornamental figures. The warp-threads are operated in sets of four 40 or more threads and having two binder warp-threads between each set, thus forming ribs lengthwise of the cloth, the weft-threads forming ribs at right angles. The dots formed at the intersection of weft and warp constitute what is known as "*petit pointe*." The 45 figuring warp-threads thus obtain a duplex character—woven single to form satin, in sets to form ribs and the outlines of figures, the binder warp-threads tying the two fabrics together.

The above describes the old way of weaving satin-face *petit pointe* goods.

To accomplish my improvement, one binder warp-thread is placed in the center of each set for binding purposes. The binder warp-threads, if of a different color from the weft-threads and of a thickness sufficient to partially cover and darken the appearance of the weft-threads, will make a factor for shading as well as binding purposes, which will be 55 readily understood by those skilled in fancy weaving, and by such persons it will be readily understood that a binder in the center of each pair, as specified and claimed in my patent, No. 353,790, though same in principle, 60 would fail to produce the shading effect desired in satin-face goods.

In satin-face *petit pointe* goods a fine weft-thread is used to intersect the warp-threads in the entire width of the fabric, and forms 70 what is known as the "satin twill," which may be woven by heddles—five, eight, ten, or more, as required.

Fabrics made twilled by the intersection of the figuring weft-threads cannot be woven 75 by heddles. I therefore use the jacquard, mounted with one hook to each thread of the pattern, and perforate the cards for twilling in single threads and in sets of four or more for the figure. A change of twill and pattern 80 can thus be made at little expense. As described in Patent No. 353,790, I also, in this improved weave, mount all the figuring warp-threads on one beam and the binder warp-threads on another beam. The binder warp- 85 threads I prefer to operate by heddles, thus: number one heddle carrying odd numbers, 1, 3, 5, &c.; number two heddle the even numbers, 2, 4, 6, &c. The weft-threads are inserted by a pick and pick-loom. Heddle 90 number one is raised for all the wefts (one or more) required by the first line of the design, and number two heddle is raised for the wefts of the second line, and thus number one and number two heddle, alternately, to the end of 95 the design. By changing number one heddle to the even numbers of the design and number two to the odd numbers a marked change is effected in the shading of figures.

The manner of arranging the warp and 100 weft threads in my present improvement is fully shown in the accompanying drawings, and which drawings form a part of this specification.

- Figure 1 represents a face view of a weave having the figuring warp-threads in sets of four, and a binder warp-thread in the center of each set, and showing a satin-face twill at the lower left-hand corner, and a shading by the interweaving of weft and binder warp at the upper right-hand corner. Fig. 2 represents a cross-section of Fig. 1. on a line of the upper shot of weft in Fig. 1. Fig. 3 represents a face view of a weave having the figuring warp-threads in sets of four and a binder warp-thread in the center of each set, and showing a satin-face twill at the lower left-hand corner, and a shading by the interweaving of weft, figuring, and binder-warps at the upper right-hand corner. Fig. 4 represents a cross-section of Fig. 3 on a line of the upper shot of weft in Fig. 3. Fig. 5 represents a face view of a weave having the figuring warp-threads in sets of four and a binder warp-thread in the center of each set, and showing a satin-face twill at the lower left-hand corner, and a shading by the interweaving of weft, figuring, and binder warp-threads at the upper right-hand corner. Fig. 6 represents a cross-section of Fig. 5 on a line of the upper shot of weft in Fig. 5. Fig. 7 represents a face view of a weave having the figuring warp-threads in sets of six and a binder warp-thread in the center of each set, and shows a satin twill at the lower left-hand corner and a shading by the interweaving of the weft figuring and binder warps at the upper right-hand corner. Fig. 8 represents a cross-section of Fig. 7 on a line of the upper shot of weft in Fig. 7.
- Referring to the drawings, similar letters and figures of reference refer to similar parts throughout the several views.
- 40 A represents the weft-threads. These wefts may all be of one color, or they may be of two or more colors, and woven "pick and pick."
- 45 1 represents the binder warp-threads; 2, the figuring warp-threads. The binder warp-threads I prefer to be finer than the figuring warp-threads. The figuring warp-threads I prefer to mount in the harness of a jacquard single—that is, a hook for each figuring warp-

thread—and arranging them in sets of four or six, with a binder warp-thread 1 in the center of each set. The binder warp-threads I prefer to mount in two heddle-frames.

We will suppose in selecting colors for one of the weaves shown in the drawings the figuring warp-threads 2 will be a dark blue, and black for the binder warp-threads 1, and red for the wefts A. I prefer the color of the binder-warp to be in strong contrast with the color of the weft, to give effect in shading the figures. The blue figuring warp-threads 2, if twilled, as shown in the lower left-hand corner of Figs. 1, 3, 5, and 7, will cover the weft A and binder-warp 1, making a satin ground. The weft and binder warps show in the drawings where twilled for a satin ground; but in a fabric beaten up in a finished state the weft and binder warp will not show on a satin face. If so desired, the warps and wefts may be so interwoven as to make a terry or damask ground, and, if so desired, the figuring warp-threads may be of alternate colors, and two or more wefts of different colors may be used, and these warps and wefts so interwoven as will produce shaded figures on a satin, terry, 75 damask, or other ground, and such fabrics may be produced by any person skilled in the art of weaving by following this specification.

Having as above fully explained my improvement and the best manner to use the same, I wish it to be understood that I do not claim, broadly, shading of figures by the interweaving of warp and weft threads different in colors, nor a satin, terry, damask, or 85 other ground weave; but

What I claim is—

In a woven figured fabric, the combination of figuring warp-threads woven in sets of four or six with a single binder warp-thread in the center of each set, and weft-threads different in color from the warp-threads, as shown, described, and for the purpose specified.

DAVID B. KERR.
